(57) **CLAIM**

The ornamental design for a bag cover, as shown and described.

DESCRIPTION

FIG. 1 is a front elevation view of a bag cover showing our new design in a state of use, the rear being an identical image thereof;

FIG. 2 is a left side elevation view thereof, the right side being an identical image thereof;

FIG. 3 is a top plan view thereof;

FIG. 4 is a bottom plan view thereof;

FIG. 5 is a bottom perspective view thereof;

FIG. 6 is a top perspective view thereof;

FIG. 7 is another perspective view thereof; shown in another configuration;

FIG. 8 is another left side elevation view, shown in an alternate state of use and the right side being an identical image thereof; and,

FIG. 9 is another front elevation view thereof, shown in an alternate state of use and the rear being an identical image thereof.

The broken lines depict portions of the bag cover and form no part of the claimed design. The remaining broken lines depicting environmental subject matter and the transparent bag in FIG. 3 form no part of the claimed design.

1 Claim, 9 Drawing Sheets
